FILAMENT TENSIONING MEANS FOR ELECTRON DISCHARGE DEVICES

Thure H. Carlstrom, Hempstead, N. Y., assignor to Sylvania Electric Products Inc., a corporation of Massachusetts

Application May 7, 1948, Serial No. 25,601

6 Claims. (Cl. 313—278)

1

The present invention relates to electron discharge devices.

In an electron tube of the type having a filamentary cathode means is used to tension the filament in order to eliminate objectionable microphonics when the tube is subjected to shock. Tensioning also prevents sagging of the filament when it is heated reducing the probability of shorting between filament and other electrodes within the tube. Known arrangements for tensioning filaments have a distinct support structure for a tensioning spring. It is especially desirable in subminiature tubes to eliminate excess structure and keep the physical tube and electrode sizes small thus improving the high frequency characteristics. As an example of a prior art practice in mounting tensioning means reference may be had to the pending application of Haas, Serial Number 441,886 in which a distinct supporting structure is supplied for mounting the tensioning spring.

An object of the invention is to provide a filament tensioning means having a minimum of parts and which is of extremely simple arrangement and compact structure. A further object of this invention is to provide a mount for the filament tensioning means which ensures transverse rigidity of the spring. It is a further object of the invention to provide an electron tube including a filamentary cathode which does not change its characteristics under exposure to shock conditions.

In one aspect the invention makes use of an existing member in the tube structure thus eliminating additional structure. A better understanding of the invention and further objects and features of novelty will be afforded by the following detailed description, considered in connection with the accompanying drawing, and those features of the invention which are believed to be novel and patentable are pointed out in the claims appended hereto.

In the drawings:

Figure 1 is a view in section along line 1—1 of Figure 2.

Figure 2 is a side elevation partly in section of an electron tube including the invention.

Figure 3 is a view in perspective of a portion of an electrode assembly including the filament tensioning means.

Figure 4 is a side elevation of Figure 2 with the envelope removed.

Referring to the drawing, the tube 11 of Figure 1, comprises an envelope 12, within which there is arranged an electrode assembly 13. The

2

electrode assembly, used for illustrative purposes, includes a two section anode, having sections 14a, 14b, a first grid 15, a second grid 16 and a filamentary cathode 17. The first grid 15 is supported upon rods 18a, 18b, and the second grid 16 is similarly carried by rods 19a, 19b. The electrodes are maintained in spaced relation by wafers 20 and 21 which are apertured to receive grid rods 18a, 18b, 19a, 19b.

10 The anode sections are maintained in the electrode assembly 13 by anode rods 22 and 23 which penetrate apertures in wafers 20 and 21, and by rods 24 and 25 which penetrate wafer 20. To complete the sturdy structure and connect anode sections 14a and 14b electrically, a bridge member 26 having ends 27 and 28 penetrates wafer 21 and is secured to both anode sections.

15 The wafers 20 and 21 are each provided with an angular slot for receiving the filamentary cathode 17 and with suitable apertures for filament rods 34 and 35. An L-shaped bracket 36 is fastened to rod 35. The filamentary cathode is provided with end tabs 37 and 38.

20 The wafers 20 and 21 are each provided with an angular slot for receiving the filamentary cathode 17 and with suitable apertures for filament rods 34 and 35. An L-shaped bracket 36 is fastened to rod 35. The filamentary cathode is provided with end tabs 37 and 38.

25 Tab 37, at one extremity of cathode 17, is fastened to rod 34, while tab 38 at the other end of the cathode is secured to the U-shaped arm 32 of tensioning spring 30. The ends 33a and 33b of the spring are fastened to bracket 36. Each half of spring 30 includes a coil 31 that encircles and is supported by bridge member 26 of the anode. To maintain different voltages on the anode and the cathode, an insulating coating 29 encases bridge member 26 within coils 31 of spring 30. It is to be noted that spring 30 is preformed, and when stressed and attached to bracket 36 and to tab 38 provides proper tension to filament 17.

30 An electric current path for filamentary cathode 17 extends through connections between lead 13c, filament rod 34, and tab 37 respectively at one end, and tab 38, spring 30, bracket 36, rod 35 and lead 13b at the other end.

35 Additional structure for mounting the spring 30 is eliminated by forming the anode bridging member 26 with an insulating cover over which the spring is mounted. Transverse rigidity achieved with the balanced two-coil spring in the aforementioned Haas application is retained in the construction here disclosed.

40 As I have described a specific embodiment of my invention, it is obvious that modifications may be made without departing from the spirit thereof. Thus the insulated bridge may alternatively support a single-coil tensioning spring; 45 and the coiled spring may be carried by a bridge

connecting sections of another electrode such as a multi-part electrostatic shield. The number of electrodes and the shape or size of the slot for the filamentary cathode may be varied.

What is claimed is:

1. An electron discharge device comprising an electrode assembly, said electrode assembly including a filament and a plural section electrode, a bridge member connecting two sections of said electrode, a stop member, an insulating cover over a portion of said bridge member, a tensioning member having an intermediate portion, a pair of helical coils and terminal portion, said helical coils encircling said bridge member and supported on said insulating cover, said terminal portion being secured to said stop member and said filament being in contact with said intermediate portion.

2. An electron discharge device comprising an electrode assembly, said electrode assembly including a filament and a plural section electrode, a bridge member connecting two sections of said electrode, a stop member, a tensioning member having an intermediate portion, a pair of helical coils and terminal portions, said helical coils encircling said bridge member and supported thereby, said terminal portions being secured to said stop member and said filament being secured to said intermediate portion.

3. An electron discharge device comprising an electrode assembly, said electrode assembly including a filament and a plural section anode, a bridge member connecting two sections of said anode, a stop member, an insulating cover over a portion of said bridge member, a tensioning member having an intermediate portion, a pair of helical coils and terminal portions, said helical coils encircling said bridge member and supported on said insulating cover, said terminal portions being secured to said stop member and said filament being secured to said intermediate portion.

10

4. A filament support for electron discharge devices including in combination with a filament, a stop member, an arched member, an insulating coating over a portion of said arched member, a tensioning member comprising an intermediate portion, a pair of helical coils and terminal portions, said helical coils encircling said arched member and supported on said insulating cover, said terminal portions being secured to said stop member, and said filament being in contact with said intermediate portion.

15

5. An electron discharge device comprising an electrode assembly including a filament and a plural section electrode, a bridge member connecting two sections of said electrode, a stop member, an insulating cover over a portion of said bridge member, a tensioning member having a central U-shaped portion, a pair of helical coils and terminal portions, said helical coils encircling said bridge member and supported on said insulating cover, said terminal portions being secured to said stop member and said filament being secured to the apex of said U-shaped portion.

20

6. An electron discharge device comprising an electrode assembly including a filament and a plural section anode, a bridge member connecting two sections of said anode, a stop member, an insulating cover over a portion of said bridge member, a tensioning member having a central U-shaped portion, a pair of helical coils and terminal portions, said helical coils encircling said bridge member and supported on said insulating cover, said terminal portions being secured to said stop member and said filament being secured to the apex of said U-shaped portion.
